UNITED STATES PATENT OFFICE.

ERNEST E. SUTHERLAND, OF MANSFIELD, OHIO, ASSIGNOR TO WESTINGHOUSE ELECTRIC & MANUFACTURING COMPANY, A CORPORATION OF PENNSYLVANIA.

TERMINAL FOR ELECTRIC HEATING UNITS.

Application filed March 24, 1924. Serial No. 701,292.

My invention relates to electric heating units and particularly to terminal members therefor.

The object of my invention is to provide a relatively small, compact and efficient terminal member for an encased heating unit.

In practicing my invention, I provide an encased, elongated heating unit comprising a heating element, a metal gib and a cover strip, with a plurality of refractory terminal supporting members. Each of the terminal-supporting members are located between the cover strip and the gib, in pockets formed in the latter member adjacent to the ends thereof and have one face in operative engagement with the surface of the cover strip and have another portion extending through an opening in the gib. A suitable terminal member is mounted on the supporting member.

In the single sheet of drawings,

Figure 1 is a top plan view of a heater embodying my invention,

Fig. 2 is an enlarged top plan view of an end portion thereof,

Fig. 3 is a view of the portion illustrated in Fig. 2, partially in side elevation and partially in longitudinal section,

Fig. 4 is a view, in side elevation, of an end portion of a modified form of unit embodying my invention, and

Fig. 5 is an enlarged, bottom plan view of the portion illustrated in Fig. 4.

A heating unit 11, of the encased type, comprises an elongated, sheet metal cover member 12 and a sheet metal gib 13 that is substantially co-extensive with the cover member 12.

A heating element that is located between the gib and the cover member, comprises a pair of strips 14 and 15, of a suitable electric-insulating material, such as mica, between which is located a strip 16, of a suitable resistor member, that may be provided with a plurality of oppositely extending lateral slots to increase the length of the current path provided thereby, in a manner well known in the art.

The width of the cover member 12 is

greater than that of the gib 13, for all but the end portions thereof. Integral flange portions 17 and 18 located at the side of the cover strip 12 are bent around the metal gib in order to securely clamp the heating element between the opposing surfaces of the metal inside of the cover member, thereby providing also a good heat path between the heating element and the outer surface of the heating unit, and at the same time providing an encased heating unit.

Referring more particularly to the construction illustrated in Figs. 1 to 3, inclusive, the metal cover member extends a short distance beyond the end of the resistor strip 16 and still further beyond the ends of the strips 14 and 15 of insulating material.

An opening 19 is provided in the cover strip 12, for a purpose to be hereinafter specified, and a second opening 21 is provided adjacent to each of the outer ends of the cover strip to permit of mounting the heating unit in its proper operative position relatively to a surface or a member to be heated thereby.

The metal gib 13 is provided at each of its ends with a two-part opening 22 extending therethrough and comprising a substantially circular portion and an elongated portion extending from the circular portion inwardly toward the heating unit proper. The circular portion of the opening 22 is located co-axially with the opening 19 in the cover member.

A refractory terminal-supporting member 23, of suitable electric-insulating material, comprises a base portion 24 that is substantially square in lateral section and a top portion 25 that is substantially circular in lateral section. The bottom surface of the base portion 24 operatively engages the inner surface of the cover strip 12 and the top portion 25 is located in and extends through the circular portion of the opening 22. The metal gib is bent away from the inner surface of the end portion of the cover member 12 in order to provide a pocket within which the base portion of the

member 23 may be located as is illustrated more particularly in Fig. 3 of the drawings.

The outer end portions of the metal gib 5 are bent at substantially right angles to the cover strip 12 and are provided, at the extreme ends, with relatively narrow tongue portions 26 that extend through suitable openings 27 in the cover strip and are then 10 bent against the outer surface of the cover strip, as is illustrated in Fig. 3 of the drawing. This construction clamps the respective terminal supporting members tightly in their proper operative positions in the 15 pockets formed in the metal gib and between the opposing surfaces of the end portions of the gib and of the cover member.

A terminal member for each end of the heating unit is constituted by a suitable bolt 20 28 and a co-operating nut 29, a washer 31 being provided underneath the nut 29 and the outer perforated end of the resistor member 16, to effect electrical connection between the end of the resistor member and 25 the terminal member. The ends of supply circuit conductors (not shown) may be suitably connected to the terminal member 28 in any manner well known in the art.

The outer end of the resistor member 16 30 is made relatively narrow as is illustrated more particularly in Fig. 2 of the drawings, and extends away from the cover member and through the rectangular portion of the opening 22, as is illustrated more particularly in Fig. 3 of the drawings, in order that the outer end of the resistor member may be located adjacent to the outer surface 35 of the top portion 25 of the terminal supporting member.

In Fig. 4 of the drawings, I have illustrated a modified form of construction, the 40 essential difference consisting in that the outer end of the metal gib is substantially co-extensive with the cover strip 12 and extends substantially parallel thereto and in operative engagement therewith, after having been bent at right angles to the cover strip. An opening 32 is provided in the gib, co-axial with the opening 21 in the cover 45 member, and any suitable securing means, such as a machine screw or bolt, employed to hold the heating unit in its proper operative position against a surface or material, is effective also to secure the outer end of 50 the metal gib against the cover member, thereby holding the terminal-supporting member 23 in its proper operative position in the pocket in the gib.

It may be noted that the heating unit 60 proper comprises two interfitting and elongated sheet metal members, one of which is substantially flat and the other of which is provided with side flanges bent therearound to hold a heating element therebetween. 65 (The inner surfaces of the gib and of the

cover member are in operative engagement with one side of an extended heating element.) It may also be noted that the terminal-supporting member is located in a pocket formed in the metal gib and held therein by the cover member, the form of the pocket being such, in co-operation with the refractory terminal supporting member, as to prevent any turning movement thereof, when once installed. 75

Various modifications and changes may be made without departing from the spirit and scope of the invention, and I desire that only such limitations shall be placed thereon as are imposed by the prior art. 80

I claim as my invention:

1. A terminal structure for an electric heater having an insulated, extended heating element, a metal gib substantially co-extensive with and operatively engaging one side of said heating element, and a sheet metal member operatively engaging the other side of said heating element and having side portions folded over said gib to enclose said heating element, said structure comprising a refractory terminal-supporting member operatively engaging the inner surface of said sheet metal member and extending through an opening in said gib, and a terminal member secured to said supporting member. 85 90 95

2. A terminal structure for an encased electric heater having an insulated, extended heating element, a metal gib substantially co-extensive with said heating element and having an opening therethrough at each end thereof, and a folded metal cover strip substantially co-extensive with said gib, said structure comprising terminal-supporting members, of refractory electric-insulating material, operatively engaging the inner surface of said cover strip adjacent to each end thereof and projecting through the respective openings in the gib, and terminal members extending through said refractory members and operatively engaging the respective ends of the heating element, said ends extending through the openings in the gib. 100 105 110

3. A terminal structure for an electric heater having an extended heating element, a metal gib in operative engagement with one side of said heating element and having pockets formed therein beyond the ends of said heating element, and a sheet metal cover member operatively engaging the other side of said heating element and having side flange portions bent over said metal gib, said structure comprising terminal-supporting members located in said pockets in the metal gib, and terminal members extending through the respective supporting members and electrically connected to the respective ends of the heating element. 115 120 125

4. A terminal structure for an electric

heater having an extended heating element, a metal gib in operative engagement with one side thereof, having a pocket formed therein adjacent one end thereof and an

opening therethrough at said pocket, and a sheet metal cover member operatively engaging the other side of said heating element, said structure comprising a refractory

terminal-supporting member located in said pocket and extending through said opening 10 and held therein by an integral portion of said cover member.

In testimony whereof, I have hereunto subscribed my name this fourteenth day of

March 1924.

ERNEST E. SUTHERLAND.
